(57) **CLAIM**

The ornamental design for a mobile device camera accessory, as shown and described.

DESCRIPTION

FIG. 1 illustrates a front perspective view of a mobile device camera accessory, in accordance with the present invention; FIG. 2 illustrates a rear perspective view of the mobile device camera accessory thereof; FIG. 3 illustrates a front elevational view of the mobile device camera accessory, thereof; FIG. 4 illustrates a rear elevational view of the mobile device camera accessory thereof; FIG. 5 illustrates a right side elevational view of the mobile device camera accessory, thereof; FIG. 6 illustrates a left side elevational view of the mobile device camera accessory, thereof; FIG. 7 illustrates a top plan view of the mobile device camera accessory, thereof; FIG. 8 illustrates a bottom plan view of the mobile device camera accessory, thereof; FIG. 9 illustrates a front perspective view of the mobile device camera accessory, a mobile device is shown to illustrate environment only and forms no part of the claimed design; FIG. 10 illustrates a rear perspective view of the mobile device camera accessory thereof; FIG. 11 illustrates a front elevational view of the mobile device camera accessory, thereof; FIG. 12 illustrates a rear elevational view of the mobile device camera accessory thereof; FIG. 13 illustrates a right side elevational view of the mobile device camera accessory, thereof; FIG. 14 illustrates a left side elevational view of the mobile device camera accessory, thereof; FIG. 15 illustrates a top plan view of the mobile device camera accessory, thereof; and, FIG. 16 illustrates a bottom plan view of the mobile device camera accessory, thereof. The broken lines in the drawing are included for the purpose of illustrating environmental subject matter and form no part of the claimed design.

1 Claim, 10 Drawing Sheets
